UNITED STATES PATENT OFFICE.

JOSEPH SHAFFER, OF DAYTON, OHIO, ASSIGNOR OF ONE HALF TO EDWARD F. COOPER, OF SAME PLACE.

HARNESS-SADDLE PAD.

SPECIFICATION forming part of Letters Patent No. 351,212, dated October 19, 1886.

Application filed May 21, 1886. Serial No. 202,857. (No model.)

To all whom it may concern:

Be it known that I, JOSEPH SHAFFER, a citizen of the United States, residing at Dayton, in the county of Montgomery and State 5 of Ohio, have invented certain new and useful Improvements in Saddle-Pads for Harness, of which the following is a full, clear, and exact description, reference being had to the accompanying drawings, forming a part of this 10 specification.

In harness-pads as ordinarily constructed the chief objection consists in the fact that they adhere closely to the skin of the animal, and frequently cause sores or galling by the 15 exclusion of the air and the retention of the sweat or moisture, and this retention of the moisture, while producing or increasing the galling, serves also to injure the pad by causing its filling to pack or harden, and when 20 dried causing the inner lining of the pad to wrinkle or become uneven, thereby rendering it more objectionable on that account.

The object of my invention is to remedy these objections, and to improve the construction of the pad, as well as its means of attachment to the saddle.

The novelty will be herein set forth, and specifically pointed out in the claims.

In the accompanying drawings, Figure 1 is 30 a perspective view of my improved saddle-pad. Fig. 2 is a bottom plan view of the same spread open. Fig. 3 is a sectional elevation in the line $x-x$ of Fig. 2. Fig. 4 is a side elevation of so much of the saddle and 35 pad as is necessary to show the method of securing them at the top.

The same letters of reference are used to indicate identical parts in all the figures.

The outer side, A, of my improved pad is 40 composed of two flaps, with the central portion at the ridge cut out, so as to leave end pieces, a a, at the front and back. The inner surface, b b, of the pad is preferably of leather, though other material might be used, which 45 has been pressed in a die or mold to form pockets extending transversely across the pad. These portions are then stitched to pieces c c, of cloth or leather, corresponding in size and shape with the outer portions, A, of the pad.

Before stitching across one of the ends of the 50 pockets they are filled with flaxseed, the advantages of the use of which will be presently explained. If desired, the parts c c may be omitted, and the under portions, b b, may be stitched directly to the outer portion, A. A 55 piece of cloth or elastic webbing, B, is made to fill the cut-out portion at the ridge, whereupon the parts are fitted together, and are secured around the edges by a binding, d, and rows of stitching.

Perforated attaching-pieces E and F are 60 stitched to the portions a, as shown, and serve as means for securing the pad to the saddle at its top in the following manner: The check-rein hook G is inserted through the perforation in the piece E, and the crupper-strap ring or loop H is inserted through the slot or perforation in the piece F.

I are the usual attaching-straps, secured to the lower ends of the upper surface of the 70 pad.

The advantages of this construction may be described as follows: By the use of the seed-filled pockets, which form corrugations or cushions extending transversely across the pad 75 and in contact with the animal, the contact-surface is very much reduced and a free circulation of air permitted. Furthermore, by the use of flaxseed as a stuffing, when the pad becomes moist the contents of the pockets do 80 not become packed and solidified, as when other stuffing material is used, and the contact-surface is preserved soft and flexible.

It will be observed that the strip of webbing B is somewhat narrower than the length 85 of the connecting-pieces a a, so that when it is stitched to the two sides of the pad it serves to arch up the pieces a a and hold them entirely out of contact with the horse's back, and causing the pad to fit snugly to the under 90 side of the saddle. By the use of the elastic webbing, or, if preferred, any other soft textile material, galling or chafing over the spine of the animal is prevented.

Having thus fully described my invention, 95 I claim—

1. A harness-pad having its central portion at the ridge cut away, leaving the two sides

- connected by end portions, and having said cut-away portion filled in with a flexible material, which connects the two sides and serves to prevent galling, substantially as described.
- 5 2. An elastic harness pad having its central portion at the ridge cut away, leaving the two sides connected by end portions, and having said cut-away portion filled in with elastic webbing, which connects the two sides and 10 serves to prevent galling, and enables the pad to be adjusted to saddles of different shapes and sizes, substantially as described.
3. A harness-saddle pad provided on its under side with transverse pockets filled with flaxseed to form cushions, substantially as described, whereby the contact surface is reduced and kept soft and flexible. 15

JOSEPH SHAFFER.
